DISPLAY HYDRATOR CABINET

Moritz C. Durszewicz, Evansville, Ind.

Application November 30, 1938, Serial No. 243,267

3 Claims. (Cl. 62—89.5)

My invention relates to cabinets and more particularly to display cabinets equipped with hydrator compartments.

One of the principal objects of my invention is to provide a display cabinet so constructed and arranged whereby a hydrator compartment is effectively insulated from an ice or moisture producing compartment in a manner to preclude freezing of food products contained within the hydrator compartment.

Another object of my invention is to provide a device of the character described equipped with means for circulating moist air from a cooling compartment about a hydrator compartment whereby the food products contained in said hydrator compartment may be impregnated with the moisture.

An important object of my invention is to provide a device of the character described which is simple in construction, durable in use, efficient in operation and economical in manufacture.

Other objects and advantages will be apparent from the following description, appended claims and annexed drawing.

Referring to the drawing wherein like reference characters designate like parts throughout the several views:

Figure 1 is a front elevation of my invention.
Figure 2 is a rear elevation thereof.

Figure 3 is a sectional view taken on the line 3—3 of Figure 2.

Figure 4 is a fragmentary perspective view of a wall of the hydrator compartment.

In practicing my invention, I provide a cabinet 5 fashioned with bottom, front, rear, top and end walls 6, 7, 8, 9 and 10 respectively. The rear wall is constructed with interiorly arranged insulating material and provided, adjacent the wall 6, with a pair of hinged doors 11 whereby access may be had to the lower section of the cabinet and said doors 11 are likewise provided with interiorly arranged insulating material. The front and end walls 7 and 10 are also constructed with interiorly arranged insulating material and which coats 45 with the other walls to effectively insulate the interior of the cabinet from the atmosphere.

The upper wall 9, adjacent the rear wall 8, is fashioned with an inclined section 12 in which are hinged a plurality of doors 13 having panes of glass therein and between which are sealed air pockets 14 serving as insulating mediums to the interior of the cabinet when the doors are in closed position. The doors 13 provide ready access to the upper section of the interior of said cabinet. The front wall 7, subjacent the top wall

9, is fashioned with a plurality of transparent panels 15 whereby a view of the contents of the upper section of the cabinet may be had. Suitable electric lamps 15a contained within reflectors 15b are secured to the top wall and afford a means for illuminating the interior of the cabinet.

Above the bottom 6, the cabinet is formed with a horizontally disposed partition 16 dividing the lower section of the cabinet into an upper moisture producing or ice compartment 17 and a lower surplus food storage compartment 18. The partition 16 adjacent the doors 11 has connected thereto the upper end of a drain pipe 19 whereby water from melting ice positioned on the partition 16 is drained from said ice compartment 15 downwardly through the compartment 18 and outwardly of the cabinet for disposal in a desired manner.

Subjacent the inclined top 12, I provide a receptacle 20 fashioned with side, end and bottom walls 21, 22 and 23 respectively and having an open top. Each of said walls are fashioned with inner and outer auxiliary spaced walls 24 and 25 respectively coacting to form therebetween an insulating compartment C entirely surrounding the sides, ends and bottom of a hydrator compartment H defined by said walls. The compartment C is filled with liquid, for instance water or the like, and the top of the side wall 24, adjacent the front wall 8, is fashioned with a laterally and outwardly extending section 26 effecting connection with the front wall 7 of the cabinet whereby to provide an air passage entirely surrounding the receptacle 20. The section 26 of the respective side wall 24 is fashioned with a plurality of louvers 27 whereby the air may circulate upwardly from the compartment 17 and over and into the hydrator compartment H.

The bottom wall 23 of the receptacle 20, adjacent the rear side thereof, has communication with the upper end of a gooseneck extending through said wall 23 whereby to drain excess moisture from the receptacle, the gooseneck serving to provide a trap for said moisture to preclude circulation of air upwardly therethrough. The outer corner of the receptacle, at the jointure of the walls 23 and 24, is provided with a drain plug 31 and likewise the upper end of said wall 24 is provided with a filler plug 32 whereby liquid may be introduced into the compartment between the auxiliary walls 24 and 25.

In use, the compartment between the auxiliary walls 24 and 25 is filled with liquid, the latter being sealed therein by the plugs 31 and 32. Food products, for instance fruit and vegetables, are

- placed within the hydrator compartment H. Ice is supplied to the compartment 17 and which serves to moisten the air and effect a circulation thereof upwardly through the air passages about the receptacle to provide the food products with moist air whereby said products are impregnated with moisture to maintain them in a fresh and wholesome condition over an appreciable long period of time.
- 10 While I have shown and described the ice compartment 17 as being adapted for the use of ice, it is to be understood that said compartment may be provided with suitable coils in which is contained a refrigerant for cooling moisture thereabout. Furthermore, the liquid in the compartment C serves to preclude freezing of the food products, thus effecting an economy in the preserving thereof.
- It is obvious that the invention is not confined to the herein described use therefor as it may be utilized for any purpose to which it is adaptable. It is therefore to be distinctly understood that the invention is not limited to the specific construction as illustrated and described, as the same is only illustrative of the principles of operation which are capable of extended application in advance forms, and that the invention comprehends all construction within the scope of the appended claims.
- 20 What I claim is:
1. A device of the character described, comprising, a cabinet provided with a moisture producing compartment, a hydrator compartment mounted within said cabinet and suspended above said moisture producing compartment, the walls of said hydrator compartment spaced from the walls of said cabinet and coacting therewith to provide an air passage about said hydrator com-

partment, said hydrator compartment having inner and outer auxiliary walls defining an insulating chamber about the hydrator compartment and said chamber provided with liquid insulating material.

2. A device of the character described, comprising, a cabinet provided with a moisture producing compartment, a hydrator compartment mounted within said cabinet and suspended above said first mentioned compartment, the walls of said hydrator compartment spaced from the walls of said cabinet and coacting therewith to provide an air passage about said hydrator compartment, said hydrator compartment having inner and outer auxiliary walls defining an insulating chamber about the hydrator compartment and said chamber provided with a liquid insulating material, and a drain trap connected with said hydrator compartment for draining the latter into said moisture producing compartment.

3. A device of the character described, comprising, a cabinet provided with a moisture producing compartment, a hydrator compartment mounted within said cabinet and suspended above said first mentioned compartment, the walls of said hydrator compartment spaced from the walls of said cabinet and coacting therewith to provide an air passage about said hydrator compartment, said hydrator compartment having inner and outer auxiliary walls defining an insulating chamber about the hydrator compartment and said chamber provided with a liquid insulating material, a drain trap connected with said hydrator compartment for draining the latter into said moisture producing compartment, and means for draining said moisture producing compartment.

MORITZ C. DURSZEWICZ.
